UNITED STATES PATENT OFFICE

2,289,159

MERCURY BOILER

Orla L. Wood, Schenectady, N. Y., assignor to
General Electric Company, a corporation of
New York

Application May 28, 1941, Serial No. 395,537

15 Claims. (Cl. 122—235)

The present invention relates to mercury boilers and like elastic fluid generators in which a substantial portion of the heating tubes are located in a convection chamber above a drum with the upper ends of these tubes connected to receive heated mercury or like operating medium from tubes located in a combustion chamber and the lower ends of the tubes connected to discharge a mixture of mercury liquid and vapor to such drum. The general arrangement of such a downward-flow convection heating tube is disclosed and covered by the patent to Nerad, No. 2,206,704, issued July 2, 1940, and assigned to the same assignee as the present application. This type of boiler may be operated with a comparatively small amount of operating fluid which during starting operation fills only the tubes in the combustion chamber while the tubes in the convection chamber are empty during starting and receive operating fluid only as the mercury in the tubes subject to radiant heat in the combustion chamber expands and is expelled from such tubes.

The general object of my invention is to provide an improved construction and arrangement of mercury boilers and like elastic fluid generators of the type above specified which may be operated economically and efficiently with a comparatively small amount of operating fluid.

A specific object of my invention is to provide an improved convection heating tube arrangement permitting a substantial increase of the convection heating surface of a boiler.

Another specific object of my invention is to provide an improved tube arrangement in a combustion chamber whereby the walls of such chamber may be substantially completely covered with a minimum number of heating tubes requiring comparatively few and short headers for conducting liquid to the lower ends of such tubes.

For a consideration of further objects of my invention and of what I believe to be novel and my invention, attention is directed to the following description and the claims appended thereto in connection with the accompanying drawings.

In the drawings, Fig. 1 illustrates a perspective view, partly broken away, of a mercury boiler embodying my invention; Fig. 2 is a perspective view of the boiler walls partly broken away; Fig. 3 is a detail view of a part of Fig. 1; Fig. 4 is a development of the tube circuits and the walls of the boiler of Fig. 1, the tubes being indicated in single, full lines, and the walls in dash-dotted lines; Fig. 5 is a single line diagram of the

tube circuit, and Fig. 6 is another detail view of Fig. 1.

The boiler, as illustrated in Fig. 2, is viewed from the rear cut along a vertical plane through the center of the boiler parallel to the side walls. The walls comprise a lower front wall 10, an upper front wall 11, a rear wall 12 and side walls 13 and 14. The lower and upper front walls 10 and 11 are connected by an inclined roof 15. The lower end portions of the front and side walls are connected by a bottom which includes an inclined bottom wall 16 connecting the side walls and the rear wall 12, a vertical bottom wall 17 and a horizontal bottom wall 18 connecting the side walls and the lower front wall 10. A horizontal, cylindrical drum 20 is supported on and secured to an opening 21 of the upper front wall 11.

The lower portions of the side, front and rear walls below the roof 15 form a combustion chamber 22 and the upper portions of the walls form a convection chamber 23. Burners, not shown, for supplying fuel and air to maintain combustion in the combustion chamber may be conveniently located in the lower portions of the rear and front walls. The walls of the combustion chamber are completely lined with heating tubes. In accordance with my invention I provide four distinct sets of heating tubes. These include a set of vertical tubes 24 lining the front wall 10 and the roof 15. The lower ends of these tubes are connected to a lower header 25 to which liquid is conducted from the drum 20 by a plurality of downtubes 26, 27 and 28. The downtube 26 is located in the corner formed between the front wall 10 and the side wall 13. The lower portion of the tube 26 is reduced in diameter and connects to the end of the lower header 25. The other downtubes 27 and 28 conduct liquid from the drum to intermediate portions of the lower header 25. The downtubes are located inside the furnace in vertical grooves or channels formed in the furnace wall. These downtubes are protected from radiant heat by the uptubes.

A second set of heating tubes 29 lines the side wall 13. These tubes are inclined and have inlet ends connected to receive mercury liquid from the aforementioned downtube 26. A number of the inclined tubes 29 covering the upper portion of the side wall 13 in the combustion space have vertical intermediate portions 30 and end portions 31 inclined in a direction opposite to the direction of inclination of the inlet portions and connected to the drum 20.

The tubes 29 include two lower end tubes 32

and 33, the first of which has a vertical portion 34 located behind the other tubes 29 and provided with a plurality of studs or brackets 34a (Fig. 6) for supporting the heating tubes 29. This support may be formed in any convenient manner, for instance, by a plurality of links connecting the vertical tube 34 to the inclined tubes 29. The second of the two lower tubes 33 has a vertical portion 35 located in the corner formed by the side wall 13 and the rear wall 12 and acting as another support for the tubes 29.

A third set of tubes 36 has portions covering the inclined bottom wall 16. The inlet ends of the tubes 36 are connected to a header 37 to which operating liquid is conducted by a conduit 38 connecting the header 37 to the aforementioned header 25.

The two headers 25 and 37 and the connecting conduit 38 between them are located in the space formed between the vertical bottom wall 17 and the lower portion of the front wall 10. The connecting conduit 38 has a flexible intermediate portion 39 to avoid the setting up of stresses due to relative expansion between the lower headers 25 and 37.

The third set of tubes 36 lining the bottom wall 16 has upper vertical portions 40 lining the central part of the rear wall 12. The vertical portions 40 are connected to the portions on the bottom wall by inclined portions 41 (see Figs. 1 and 4).

A fourth set of heating tubes 42 is arranged to cover the side wall 14. These tubes are inclined and in all respects similar to the tubes lining the other side wall 13. In particular, the tubes 42 have inlet ends connected to a downtube 43 for receiving mercury liquid from the drum 20. The downtube 43 for the tubes 42 corresponds to the downtube 26 for the tubes 29. The tubes 42 are supported by two vertical tubes 44 and 45 which form continuations of the two lowermost inclined tubes 42 and correspond to the tubes 34 and 35 on the wall 13. Some of the tubes 42 near the upper portion of the combustion chamber are bent to form vertical portions 46 and oppositely inclined portions 47 connected to the drum 20. Thus, the tubes 29 and 42 in the upper portion of the combustion chamber line the side walls 13 and 14 respectively and have ends connected to the drum 20. The tubes 29 located in the lower portion of the combustion chamber are extended to form vertical tubes 48 lining the left-hand portion of the rear wall 12. These vertical tubes 48 are connected to the tubes 29 by inclined tubes 49 lining the rear wall 12 adjacent the aforementioned inclined tubes 41. The angle of inclination of the portions 49, as best shown in Fig. 4, is the same as the angle of inclination of the tubes 29. The tube portions 41 and 49 are so arranged that they cover substantially uniformly the lower portion of one-half of the rear wall 12.

The inclined tubes 42 covering the lower portion of the side wall 14 are likewise extended to form inclined portions 50 and vertical portions 51 covering the right-hand half of the rear wall 12, as viewed in Fig. 2.

In order to reduce the amount of mercury liquid necessary for operating the boiler I provide in accordance with my invention a plurality of vertically spaced banks of heating tubes in the convection chamber 23. In the present instance I have indicated two banks of tubes, a bank 52 (Fig. 1) located in the lower portion of the convection chamber and a bank 53 located in the upper portion of the convection chamber. The

lower bank 52 comprises a plurality of horizontally spaced sets of tubes. Each set has a number of series-connected hairpin-shaped portions. The lower or outlet end of each set of the banks 52 and 53 is connected to the drum 20. The upper ends of the sets of tubes of the lower bank 52 are connected to the upper ends of alternate tubes 40, 48 and 51. In the present instance I have shown two sets of tubes for the bank 52. The front set of the bank is connected to the first tube 40 shown on the right-hand side of Fig. 1 and at the left-hand end of Fig. 4. The second set of the bank 52 located behind the first set when viewed in Fig. 1 is connected to the third tube 49. In other words, if we give the tubes 40 consecutive numbers, then the sets of tubes of the lower bank 52 are connected to the uneven numbers of the tubes 40. The sets of tubes forming the bank 53 are connected to the even numbers of the tubes 40 and 48. Thus, the first set of tubes of the bank 53 is connected to the second tube 40 from the right in Fig. 1 and from the left in Fig. 4. The second set of tubes of the bank 53 is connected to the 4th tube 40 from the right in Fig. 1 and from the left in Fig. 4. In this manner the upper ends of the tubes covering the rear wall 12 are connected to the upper ends of the vertically spaced banks of tubes 52 and 53. With the provision of two banks 52, 53 the even numbers of the tubes covering the rear wall 12 have upper ends connected to one bank of tubes and the uneven numbers have upper ends connected to the other bank of tubes.

During starting, as pointed out above, the boiler is filled with mercury liquid to a point near the level of the drum, little mercury being contained within the drum. The banks of tubes located in the convection space are of considerable length. Therefore, during the starting operation without the provision of further means it would take considerable time until the mercury contained in the tubes in the combustion chamber were forced through the banks 52, 53 and returned to the drum and recirculated through the downtubes and the tubes in the combustion chamber. Means are provided to effect circulation shortly after the starting period and thereby to eliminate the danger of the boiler running dry and of overheating certain riser and connecting tubes. These means in accordance with my invention include tubes connecting a portion of the uptubes near the level of the drum to the drum and other tubes for conducting mercury liquid to intermediate points of the banks 52 and 53.

More specifically, each tube for conducting liquid to the upper end of a set of tubes of the bank 53 has a lower end portion 54 (Figs. 1 and 3) aligned with a corresponding end portion 55 of one of the tubes 40, 48 and 51 and enclosed in a chamber 56. Each chamber 56 is connected by a pipe 57 to a drain header 58 for conducting mercury liquid to the drum 20. The chambers 56 are located slightly above the cold liquid level in the drum 20. During starting, radiant heat transmitted to the mercury in the combustion chamber causes expansion of the mercury liquid whereby some of the liquid spills over from the end portions 55 into the chamber 56 and is recirculated through the drain header 58 and the drum through the downtubes and the combustion heating tubes. During normal operation the major portion of the liquid expelled from the tubes 55 is forced into the tube portions 54 and conducted to the upper ends of the sets of tubes of the bank 53. In

these tubes a substantial amount of the liquid is evaporated and the mixture of vapor and liquid is discharged from the lower ends of the tubes into the drum.

The second means for preventing overheating of the tubes in the combustion chamber by increasing the circulation during the starting period comprise a plurality of tubes for conducting mercury liquid from the upper ends of the tubes 24 lining the front wall 10 and the roof 15 to intermediate portions of the sets of tubes of both banks 52, 53. Thus, as shown in Fig. 1, the tube 24 shown on the right-hand side has a portion 59 lining the roof 15 and forming an extension 60 connected to an intermediate point of the first or front set of tubes of the bank 52. The second tube from the right lining the front wall 10 has an extension 61 connected to an intermediate point of the first set of tubes of the bank 53. The third tube from the right lining the front wall 10 in Fig. 1 is connected to an intermediate point 62 of the second set of tubes of the bank 52 and the fourth tube 24 from the right in Fig. 1 is connected to an intermediate point 63 of the second set of tubes of the upper bank 53. In other words, with the tubes 24 consecutively numbered, the uneven tubes 24 are connected to intermediate points of the set of tubes of the lower bank 52 and the even numbers of the tubes 24 are connected to intermediate points of the set of tubes of the upper bank 53. Conduit means 65 are connected to the drum 20 for conducting mercury liquid thereto. Mercury vapor is discharged from the drum 20 through discharge conduit 66. The lower portion of the drum contains a known type of displacement block 67 for displacing mercury liquid therein.

The heating tubes located in the combustion chamber are filled with mercury liquid to a level slightly above the connection of the drum 20 with the mercury liquid supply conduit 65. During starting, the mercury liquid contained in the heating tubes expands and as the liquid level rises beyond the upper end portions 55 of the heating tubes 40, 48, which end portions are located at a level slightly above the cold liquid level in the drum, mercury liquid overflows the upper end portions 55, as explained above, and is passed through the connectors 57 and the drain header 58 to the drum. With further rise in temperature the mercury liquid contained in the inclined tubes 29 and 42 on the upper portions of the side walls 13 and 14, respectively, is forced through the outlet portions 31 and 47 of said tubes into the drum 20, whence the liquid is recirculated. With increasing mercury temperature, further recirculation through the drum takes place as soon as the mercury rises to the intermediate points of the lower bank 52 to which some of the tubes 24 are connected. With further increasing temperature, the mercury reaches the upper ends of the tubes of the banks 52 and finally the intermediate points 63 of the upper bank 53 and, as normal operation takes place, the mercury rises to the upper ends of the tubes of bank 53 and is discharged therefrom to the drum. During normal operation a mixture of mercury liquid and vapor is continuously discharged from all tube circuits into the drum 20. The mixture is separated in the drum, the liquid being recirculated through the downtubes and the vapor discharged through the discharge conduit 66.

Thus, with the tube arrangement described

above, mercury liquid is fed to the tubes in the convection chamber at various elevations, thereby preventing overheating of the tubes. Mercury is fed to those portions of the banks first which are located nearest the combustion chamber and mercury liquid is conducted to those banks or bank portions last which are located farthest away from the combustion chamber and are subjected to lower flue gas temperatures.

The combustion chamber described above is substantially rectangular in cross section and has front and rear walls lined with substantially vertical tubes and side walls lined with inclined or sloping tubes. The sloping side wall tubes have extensions turning onto and lining the front wall or a part thereof. Another part of the front wall, in the above example the central portion of the front wall, is lined with tubes connected to or forming extensions of a row of tubes lining the bottom of the combustion chamber. With this arrangement it is possible completely to line all of the walls with comparatively few tube circuits and at the same time without requiring crossing of the tubes in the convection chamber.

The entire boiler arrangement of drum, downpipes and uptubes is preferably suspended from a supporting structure 68 near the lower end of the convection chamber 23, that is from the same elevation near the top of the boiler to permit relative expansion between the boiler casing and the tube system. This is especially true with regard to the support of the sloping side wall tubes by vertical risers or cooled supporting tubes held near the top. The banks in the convection space, sometimes called fog banks, may also be supported by cooled riser tubes on one side and the discharge tubes from the upper bank or banks 53 on the other side of the bank 52 in a manner similar to the arrangement shown in Fig. 6. The bank or banks 53 may be supported by compression spacers 70 between the tubes, the bottom or discharge tubes 71 of bank 53 acting as the supporting columns.

The boiler requires only single comparatively short and direct downpipes to few lower interconnecting headers which also act as equalizers for the circulating system and are arranged substantially vertically below the drum. The corner downpipes act as headers to feed the sloping side wall tubes. In some instances, such as where the boiler is used for ship-propelling purposes, the smallest variation in the lower header pressure is insured, thus maintaining the pumping ability of the tubes with the roll and pitch of a ship.

The tubes from the two lower headers line all of the walls in the combustion chamber. This is accomplished by having the upward sloping tubes covering the side walls turn the corner onto the front wall with the same slope until they meet their lower adjacent tube. At that point they turn vertically upward to cover completely the right-hand and left-hand portions of the front wall. The tubes covering the floor or bottom bend up onto the front wall and cover the intermediate portion thereof. The entire tube arrangement in the combustion chamber actually includes only three groups of tubes, one covering the rear wall and ceiling, the other two covering the side walls and the front wall. This reduces the number of tube circuits in the boiler, makes each circuit longer and all circuits of substantially equal length, thereby effecting approximately equal pick-up of radiant heat. The increased length of each circuit and the uniform

and increased radiant heat pick-up produce an increased pumping action sufficient to lift the mixture of liquid and vapor formed in the tubes of the combustion chamber a considerable height above the normal level in the boiler drum to the upper ends of the banks of heating tubes in the convection chamber.

Substantially each tube in the combustion chamber passes along at least two walls of the furnace, thereby insuring substantially uniform heat pick-up by the tubes.

What I claim as new and desire to secure by Letters Patent in the United States is:

1. A mercury boiler having walls forming a combustion chamber and a convection chamber above the combustion chamber, a drum located at a level near the lower end of the convection chamber, heating tubes lining the walls in the combustion chamber, means including headers located substantially vertically below the drum for conducting mercury liquid from the drum to the lower ends of the heating tubes, and a plurality of vertically spaced separate banks of tubes located in the convection chamber and having upper ends separately connected to the tubes in the combustion chamber to receive heated mercury therefrom and lower ends connected to the drum.

2. A mercury boiler comprising walls having lower portions forming a combustion chamber and upper portions forming a convection chamber, a drum, up tubes lining the walls in the combustion chamber, means including down tubes for conducting mercury from the drum to the lower ends of the up tubes, and a plurality of vertically spaced independent sets of tubes located in the convection chamber above the drum and having upper ends separately connected to separate up tubes and lower ends connected to the drum.

3. A mercury boiler comprising walls forming a combustion chamber and a convection chamber above the combustion chamber, a plurality of heating elements located in the combustion chamber, means for conducting mercury liquid to the lower ends of the heating elements, a plurality of vertically spaced independent banks of tubes located in the convection chamber having upper ends separately connected to receive heated mercury from the heating elements, and means connected to the lower ends of the banks of tubes for receiving a mixture of mercury and vapor formed therein.

4. A mercury boiler comprising walls forming a combustion chamber and a convection chamber above the combustion chamber, heating tubes lining the walls of the combustion chamber, means including a drum for supplying mercury liquid to the lower ends of the heating tubes, a bank of heating elements located in the convection chamber above the level of the drum, means connecting the upper ends of the heating elements to the upper ends of some of the heating tubes, means connecting intermediate points of the heating elements to other heating tubes, and means connecting the lower ends of the heating elements to the drum.

5. A mercury boiler comprising walls having lower portions forming a combustion chamber and upper portions forming a convection chamber, a drum located near the lower end of the convection chamber, heating tubes lining the walls in the combustion chamber, means including downcomers for conducting mercury liquid from the drum to the lower ends of the heating tubes, a bank of heating elements located in the

convection chamber having lower ends connected to discharge mercury into the drum, and separate means for connecting the upper ends and intermediate portions of the heating elements to the heating tubes.

6. A mercury boiler comprising walls having lower portions forming a combustion chamber and upper portions forming a convection chamber, a drum located at a level near the lower end of the convection chamber, heating tubes lining the walls in the combustion chamber, means for conducting mercury from the drum to the lower ends of the heating tubes, a plurality of vertically spaced banks of tubes located in the convection chamber and having upper ends connected to separate heating tubes in the combustion chamber and lower ends connected to the drum, and means for conducting heated mercury to intermediate points of at least some of the banks of tubes.

7. A mercury boiler comprising walls having lower portions forming a combustion chamber and upper portions forming a convection chamber, a drum located at a level near the lower end of the convection chamber, heating tubes lining the walls in the combustion chamber, means for conducting mercury from the drum to the lower ends of the heating tubes, a bank of heating tubes located in the convection chamber, means for connecting each heating tube of the bank to a heating tube in the combustion chamber comprising connecting chambers located above the cold liquid level in the drum and sealed to spaced aligned portions of the heating tubes in the combustion chamber and the convection chamber to form an overflow for mercury discharged from the heating tubes in the combustion chamber, and means including a drain header for conducting mercury from said connecting chambers to the drum.

8. A mercury boiler comprising walls having lower portions forming a combustion chamber and upper portions forming a convection chamber, a drum located at a level near the lower end of the convection chamber, heating tubes lining the walls in the combustion chamber, means for conducting mercury from the drum to the lower ends of the heating tubes, a bank of heating tubes located in the convection chamber above the drum and having lower ends connected to discharge mercury into the drum, means for connecting the upper ends of the bank of heating tubes to separate heating tubes in the combustion chamber, and means including a drain header communicating with the connecting means for conducting some of the mercury expelled from the heating tubes in the combustion chamber to the drum.

9. A mercury boiler comprising walls having lower portions forming a combustion chamber and upper portions forming a convection chamber, a drum located at a level near the lower end of the convection chamber, heating tubes lining the walls in the combustion chamber, means for conducting mercury from the drum to the lower ends of the heating tubes, a plurality of vertically spaced banks of heating tubes located in the convection chamber with lower ends connected to discharge mercury into the drum, some of the heating tubes in the combustion chamber having upper ends directly connected to the drum, means for separately connecting the upper ends of the other heating tubes to the upper ends and to intermediate

points of the banks of tubes, the last-named means including connecting chambers forming overflow arrangements at a level above the cold liquid level in the drum with regard to mercury expelled from the upper ends of the heating tubes, and means including a drain header for conducting mercury from the overflow arrangements to the drum.

10. A mercury boiler having front, rear and side walls forming a combustion chamber, a drum located at a level near the upper end of the chamber, a plurality of sets of heating tubes lining the walls in the combustion chamber and including a first set of vertical tubes lining the front wall, second sets of inclined tubes lining the side walls, the second sets having extensions lining the rear wall, means for conducting mercury liquid from the drum to the heating tubes comprising a plurality of downtubes having upper ends connected to the drum, and a lower header connecting the lower ends of the downtubes to the lower ends of the first set, two of the downtubes being located in the corners formed between the front and side walls and forming headers for the second sets of tubes.

11. A mercury boiler having front, rear and side walls and an inclined bottom, a drum located above the combustion chamber, lower header means located near the front wall substantially vertically below the drum, downcomers adjacent the front wall for conducting mercury liquid from the drum to the header means, two of the downcomers being located in the corners formed between the front and side walls, and a plurality of sets of heating tubes lining the walls in the combustion chambers and including a first set of vertical heating tubes lining the front wall and connected to receive mercury from the header means, second sets of inclined heating tubes lining the side walls and connected to said two downcomers, a third set of heating tubes lining the bottom and the rear wall, and conduit means for connecting the third set of heating tubes to said header means.

12. A mercury boiler having front, rear and side walls and an inclined bottom, a drum located above the combustion chamber, lower header means located near the front wall and substantially vertically below the drum, downcomers adjacent the front wall for conducting mercury liquid from the drum to the header means, two of the downcomers being located in the corners formed between the front and side walls, and a plurality of sets of heating tubes lining the walls in the combustion chamber and including a first set of vertical heating tubes lining the front wall and connected to receive mercury from the header means, second sets of inclined heating tubes lining the side walls and connected to said two downcomers, the second

sets of heating tubes having extensions lining outer portions of the rear wall, a third set of heating tubes lining the bottom and having extensions lining the intermediate portion of the rear wall, and conduit means for conducting mercury liquid from the header means to the third set of heating tubes.

13. A mercury boiler comprising front, side and rear walls forming a combustion chamber, a drum located near the upper end of the chamber, heating tubes lining the walls in the chamber and including a set of inclined tubes lining one of the side walls, means for conducting mercury liquid to the tubes including a downcomer located in the corner formed between said side wall and the front wall, said downcomer being connected to said set of tubes, and means for supporting said set of tubes comprising a vertical tube forming an extension of one of the set of tubes and located behind the others of said set of tubes and a plurality of supporting members secured to said extension for engaging the other tubes.

14. A mercury boiler having front, rear and side walls with lower portions forming a combustion chamber and upper portions forming a convection, the convection chamber having a cross-section smaller than that of the combustion chamber, an inclined roof connecting the lower and upper portions of the front wall, an inclined bottom connecting the rear wall and the side walls, means including an extension of the front wall to form a channel below the combustion chamber, a horizontally disposed cylindrical drum located above the roof, heating tubes lining the walls in the chambers, means for conducting mercury to the lower ends of the tubes comprising a header disposed in the channel and a plurality of downtubes adjacent the front walls and connecting the headers to the drum, and banks of tubes disposed in the convection chamber and connected to receive heated mercury from the heating tubes and discharge it into the drum.

15. A mercury boiler comprising walls forming a heating chamber, a drum located at a level between the lower and upper levels of the chamber, a plurality of heating tubes having lower and upper portions disposed within the lower and upper parts of the heating chamber with the upper portions connected to discharge heated mercury to the drum and the lower portions arranged to receive mercury liquid to be heated, connecting chambers between the lower and upper portions located at a level near the cold liquid level in the drum, and auxiliary tubes for conducting part of the mercury discharged into the connecting chambers to the drum to assure circulation of mercury during starting of the boiler.

ORLA L. WOOD.
